HAMMER

Leslie John Rapien, Chicago, Ill.

Application May 22, 1939, Serial No. 275,069

1 Claim. (CL 1-45)

The present invention relates to new and useful improvements in hammers of the handle magazine type for use particularly by lathers and roofers and has for its primary object to provide, in a manner as hereinafter set forth, a tool of this character embodying novel means for delivering nails one at a time to the head of said device to be started.

Other objects of the invention are to provide a hammer of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a magazine hammer constructed in accordance with the present invention.

Figure 2 is a top plan view thereof.

Figure 3 is a view in vertical longitudinal section through the tool, taken substantially on the line 3-3 of Figure 2.

Figure 4 is a view principally in side elevation but with a portion broken away in longitudinal section through one side portion of the device.

Figure 5 is a cross sectional view, taken substantially on the line 5-5 of Fig. 3.

Figure 6 is a detail view in perspective of the plunger.

Figure 7 is a detail view in perspective of the follower.

Figure 8 is a perspective view of one of the nails.

Figure 9 is a view in side elevation of a portion of a strip of nails to be mounted in the magazine.

Referring now to the drawings in detail, it will be seen that the embodiment of the invention which has been illustrated comprises a handle 1 of any suitable dimensions and material, said handle including finger receiving indentations 2 on one end portion. On the other end of the handle 1 is a head which is designated generally by the reference numeral 3.

As illustrated to advantage in Figs. 3 and 4 of the drawings, the handle constitutes a magazine for the reception of nails 4. Toward this end, the handle 1 has formed therein and extending from end to end thereof a substantial-

ly T-shaped groove or channel 5 for slidably receiving the correspondingly shaped nails 4. Communicating with the groove 5 is a longitudinal slot 6 in the upper portion of the handle 1. Operable in the groove 5 is a substantially T-shaped follower 7 of suitable metal which is adapted to feed the nails 4 to the head 3 of the hammer. Rising from the top of the follower 7 is a headed pin or the like 8 which the slot 6 accommodates. On the forward end portion of the handle 1 is a substantially segmental casing 9 in which a clock spring 10 is mounted. The clock spring 10 emerges from the casing 9 and extends along the upper portion of the handle 1 and terminates, at one end, in a loop 11 which is engageable with the pin 8 for connecting the follower 7 to said spring 10 for actuation thereby. The free end portion of the elongated loop 11 is turned upwardly at an angle in a manner to provide a grip 12.

The head 3 comprises an elongated housing 13 which is substantially square in horizontal section, said housing being of any suitable metal. Of course, the housing 13 extends at right angles to the handle 1. Mounted in the upper end portion of the housing 13 is a hatchet blade 14. Mounted in the lower end portion of the housing 13 is a striking member or nose 15 of suitable metal.

Mounted in the lower rear portion of the housing 13 is a vertical guide 16 the upper portion of which communicates with the groove 5 in the handle 1 for receiving the nails 4 therefrom. It may be well to here state that the guide 16 will receive but one of the nails 4 at a time. The nail slideway in the guide 16 extends through the nose 15, as at 17. Mounted for vertical movement in the housing 13 is a plunger 18 of suitable metal. Mounted on the rear of the plunger 18 and extending in spaced parallelism therewith is a finger 19 which is operable in the guide 16. Formed in the plunger 18 at an intermediate point is a recess or notch 20. The recess or notch 20 is for the reception of the forward end portion of a spring projected latch 21 which is slidably mounted in the handle 1 and which extends into the housing 13. A retracting or disengaging handle 22 is provided on the rear end of the latch 21, said handle being operable in a longitudinal slot 23 which is provided therefor in the handle 1. In Figure 9 of the drawings, there is illustrated a portion of a strip of the nails 4 which are secured together by adhesive tape 24.

It is thought that the manner in which the tool

is used will be readily apparent from a consideration of the foregoing. Briefly, the clock spring 10 is disconnected from the follower 7 and said follower is removed from the handle 1. A strip 5 of nails is then inserted in the groove 5 of the handle 1, after which the follower 7 is placed in said groove behind said nails and the clock spring 10 again connected thereto. Thus, the nails 4 are being constantly urged forwardly in 10 the handle 1 toward the head 3. However, as hereinbefore mentioned, only the forwardmost nail may enter the guide 16. The surface into which a nail is to be driven is then struck with the head 3 and when this occurs the plunger 18 15 is caused to move downwardly in the housing 13 by inertia. In this manner the finger 19 is moved downwardly in the guide 16 carrying with it the forwardmost nail which is therebeneath and impaling said nail in the surface which has 20 been struck. The nail is thus started. When the plunger 18 is in lowered position it is locked by the engagement of the latch 21 in the recess or notch 20. The driving of the nail may then be completed. The latch 21 is then retracted 25 through the medium of the thumb piece or handle 22 for releasing the plunger 18 and permitting said plunger to be returned to raised position in the housing 13, as seen in Fig. 3 of the drawings. The spring 10, through the follower 7, then 30 functions to move the next nail into the guide 16 beneath the finger 19 and the tool is ready to

repeat the above described operation. A spring 5 pressed pawl 25 is pivotally mounted in the head 13 and operable in the guide 16 for preventing the nail in said guide from dropping out.

It is believed that the many advantages of a 5 magazine hammer constructed in accordance with the present invention will be readily understood and although a preferred embodiment of the device is as illustrated and described, it is to be understood that changes in the details of 10 construction and in the combination and arrangement of parts may be resorted to which will fall within the scope of the invention as claimed.

What is claimed is:

A hammer of the class described comprising a handle having a longitudinal groove therein for the reception of nails, a head on one end of said handle, said head including a housing, a guide in said housing communicating with the groove 20 in the handle for receiving the nails therefrom one at a time, a spring actuated follower in the groove for feeding the nails to the guide, a plunger slidably mounted in the housing, a finger 25 on said plunger operable in the guide and engageable with the nails for ejecting said nails from the head, and a spring projected latch slidably mounted in the handle and engageable with the plunger for releasably locking said plunger in lowered position.

LESLIE JOHN RAPIEN.
